UNITED STATES PATENT OFFICE.

ENRIQUE ABARCA, OF SAN JUAN, PORTO RICO.

SUPPORT FOR EXPANDING METAL ARTICLES.

1,300,091.

Specification of Letters Patent. Patented Apr. 8, 1919.

Application filed October 11, 1917. Serial No. 196,095.

To all whom it may concern:

Be it known that I, ENRIQUE ABARCA, a citizen of the United States, and a resident of San Juan, Porto Rico, have invented a new and Improved Support for Expanding Metal Articles, of which the following is a full, clear, and exact description.

Among the principal objects which the present invention has in view are: to avoid unequal expansion of metal articles when re-heating the same; to avoid unequal stresses in articles of the character mentioned during the re-heating thereof; and to equalize the internal stresses of expansion set up in articles while re-heating the same.

Drawings.

Figure 1 is an end view of a support of the character mentioned constructed and arranged in accordance with the present invention, said support being shown in conjunction with a fragment of a macerating roll for sugar mills;

Fig. 2 is a top plan view of the support, the fragment of the roll being removed.

Description.

Heretofore it has been the custom when mounting on driven shafts, heavy metal rolls, to key or shape the shaft to form key members extended toward the cylindrical contour thereof. Over the shaft a metal roll or other member is slipped having been prepared with recesses or pockets corresponding with the keys or projections of the shaft.

In good practice, when the roll and shaft are in service, they are rigidly connected to avoid any chattering or vibrating. This has been accomplished by providing a bore in the roll, said bore being of a size to snugly fit the shaft that is to be placed therein. The roll is then re-heated to expand the metal and to enlarge the bore sufficient to pass the keys or other projections on the shaft, if the shaft be provided with such. If, on the other hand, the bore is slightly less than the shaft, it being intended to form what is known as a hug fit, the roll is expanded until the shaft can be passed through the bore. This is usually accomplished by placing the roll or article to be expanded in a suitable chamber where heat is applied

to the said roll or sleeve. The heat is applied most conveniently to one side of the article being expanded, with the frequent result that the expansion is unequal and the bore is destroyed. When this occurs, the contraction of the roll fails to correct the distortion and an imperfect construction results.

To avoid the difficulties above enumerated, the present invention provides a base block 7, which may be suitably disposed in a re-heating furnace or chamber. The base block 65 7 has recesses 8 and 9. The recesses 9 form bearings for trunnions 10 and 11. The recesses 8 form housings for solid supporting rolls 12, which in service extend under the roll or sleeve 13 when placed in the re-heating furnace for expansion.

Integrally connected with the trunnions 10 are worm wheels 14, the teeth whereof engage the threads of worms 15. As seen best in Fig. 2 of the drawings, the worm 75 wheels 14 extend beyond the ends of the block 7, and the shaft 16 on which are carried the worms 15, is mounted in bearings formed in the sides of the brackets 17.

The shaft 16 may be extended to any suitable distance and beyond the confining wall for heating the chamber. A hand wheel 18 is mounted on the shaft for operating the same.

It will now be observed that when the roll 85 or sleeve, as indicated by the numeral 13 in Fig. 1 of the drawings, is to be re-heated, it is placed in the heating chamber upon the rolls 12. When the heating process is inaugurated, an attendant rotates the shaft 16 90 and worms 15 mounted thereon by means of the wheel 18. The roll or sleeve 13 is slowly rotated or turned on its center, and in this manner, the heat which is applied to expand the same is evenly distributed throughout 95 the mass thereof.

Claims:

1. An apparatus as characterized comprising a base block having upwardly opening recesses and bearings formed therein; 100 a plurality of supporting rolls adapted to rest within said recesses and provided with bearing members corresponding with the bearings in said base block; a plurality of worm wheels rigidly connected with said 105 rolls for rotating the same; and a worm

shaft adapted to be rotated manually and operatively engaging said worm wheels to rotate the same in unison.

2. An apparatus as characterized comprising a base block adapted for disposition in a heating chamber and having upwardly opening recesses and bearings formed therein; a plurality of rolls removably mounted

in said recesses and bearings, the bearings of each of said rolls being integrally provided with corresponding worm wheels; and a shaft having worm sections integrally formed thereon, said shaft extending beyond the heating chamber for manipulation beyond the walls thereof.

ENRIQUE ABARCA.
